BLOWER WHEEL AND IMPELLER

Marion I. Levy, Cleveland, and Arthur Bennekamper, Parma, Ohio, assignors to Viking Air Conditioning Corporation, Cleveland, Ohio

Application May 14, 1937, Serial No. 142,608

11 Claims. (Cl. 230—134)

This invention relates to blower wheels on centrifugal pumps or fans and particularly to the rotor section technically known as the impeller.

The principal object of the invention is to provide an economical and expeditious method of constructing centrifugal type blowers.

Another object is to construct blower wheels of a more durable structure and having a more even dynamic and running balance.

10 A further object is to construct blower wheels, utilizing a novel and simple means for attaching the blades to the side rings in a truer and more uniform manner.

These and other objects of our invention are 15 more fully set forth hereinafter, reference being made to the accompanying drawing, in which like parts are designated by like reference characters and in which:

Figure I is a perspective view of the blower wheel;

20 Figure II is an enlarged view of a section of a side ring showing position of sockets embossed therein;

Figure III is a cross sectional view of a side ring taken along line III—III of Figure II.

25 Figure IV is a sectional view of a side ring and blades showing steps in assembling the same;

Figure V is a sectional view of a side ring and a blade just before assembly taken along line V—V of Figure IV;

30 Figure VI is a sectional view of a side ring and a blade after assembly taken along line VI—VI of Figure IV;

Figure VII is a sectional view of a side ring, 35 after the tab is squeezed into the embossed socket, taken along the line VII—VII of the Figure VI;

Figure VIII is a view of a blade showing formation of end-stay and tab on the end of a curved blade, taken along the line VIII—VIII of 40 Figure V.

Figure IX is a sectional view of a side ring and blade tab taken along the lines IX—IX of Figure II, similar to the view of Figure VI, excepting that the blade tab is shown as being welded instead of peened to the side ring.

45 Heretofore, in the manufacture of blower wheels, it has been the practice in assembling the rotor section or impeller, to rivet the blades to the side rings, or to have horizontal tabs on the blades extend through slots in the rings and bent over on the outside. Either of these methods of construction and assembly have a tendency to unbalance the wheel. The weld or rivets could not always be uniformly spaced and as a result, 50 all of the blades were not always parallel or

evenly set at the correct angle. Furthermore, the welding particularly, it being a manual operation, was not always uniform. Sometimes too much heat applied at one spot would cause the ring to warp and again at other times, depositing 5 a trifle more of metal at one joint than at another, would throw the wheel considerably off balance.

In the method of construction using horizontal end tabs projecting through the rings, it is a comparatively simple matter to attach all the blades to one ring, but it is more difficult to place the second ring over the assembled blades, as each blade has to be in exactly the right position for the tabs to engage all the slots simultaneously. 10 To get all the blades in the proper position was time consuming and fans of this type of construction were therefore, expensive to manufacture.

A slightly unbalanced wheel could operate reasonably well at comparatively low speeds, but in the more advanced types of blowers, and those which depend upon high speed for efficiency and satisfactory operation, the blower wheel must be in dynamic balance at all times and must be able 15 to retain this balance without warping or being subject to distortion.

The centrifugal type of blower wheel to which our invention relates consists of a shaft 13, on which is mounted by means of the radial braces 30 or spokes 19, the impeller section composed of the side rings 11 and the blades 12.

The rings 11, are stamped out of suitable flat metal; are in reality flat uniformly circular endless hoops; and are embossed so as to form channels or sockets 14 on their inside surfaces. The raised or embossed portion of the ring 11, is somewhat quadrilateral in form and has two slots 15 and 16 in the parallel sides. The sockets 14 are annularly and evenly spaced around the ring 35 11, are set at an angle, and so made that the longest side, having the slot 15 is easily reached, to facilitate assembly. The sockets 14 are also deep enough to permit the tabs 17 to go through the slots 15 and 16 easily and smoothly. The required embossment or lateral depth of the socket 14 is dependent upon the thickness of the metal 40 at the tabs 17. The uniformly correct angle at which the blades 12 are affixed to the rings 11, is easily controlled by the regular positioning of the 45 shoulders of the end-stays 18 firmly against the rims of the sockets 15.

The blades 12 are also made of metal strips curved longitudinally and which have arcuate 50 end-stays 18 and tabs 17 on their curved ends. 55

The end-stays 18 serve to strengthen the blade, preserve its curvature and acts as a guide for the correct positioning of the tab 17 in the socket 14. The tab 17 attached to the end-stay 18 is somewhat pointed or triangular in shape and fits into the slots 15 and 16 as shown and is securely fastened therein by peening as indicated in the Figures VI and VII, or by welding, brazing or soldering as indicated by the character 20, in Figure IX. The weld, braze or solder should not extend out beyond the outside surface of the side ring, but should be confined within the embossed depression, herein termed a cup and designated by the character 21; otherwise the additional projecting metal might cause the blower wheel to lose its running balance when revolving at comparatively high speeds.

In the commercial assembly of a wheel, the two side rings 11 are placed in a jig and held parallel to each other; both ends of a blade are attached to the two rings simultaneously; and the rings 11 are squeezed or peened at the sockets 14; so that the portion of a tab 17 is forced into the hollow space or cup 21 in the ring 11 caused by the embossing of the socket 14. The operation of thus joining the blades to the rings is carried on progressively until all the blades are in position and the wheel is complete. The wheel is then mounted on a suitable shaft 13 by means of the radial braces or spokes 19.

Because of the closeness of the blades 12 to each other, the last blade could not be conveniently installed, unless the tabs 17 thereon were easily accessible to the slots 15. Therefore in placing the last blade it is necessary to slide the tabs thereon first in an axial direction between the rings 11 and then in an arcuate direction to engage the sockets. By making the tabs 17 pointed and the entrance slot 15 longer the speed at which the parts are assembled is greatly increased.

However, when the blower wheels are automatically assembled, the tabs 17 would not necessarily have to be pointed nor would the sockets 14, have to be embossed in the particular angle or be of the particular shape illustrated. The tabs 17, for instance could be square or round instead of as shown, or have any other shape adaptive to automatic assembly.

While we have described the invention in its preferred form, and while we have used certain terms and language, it is understood that the embodiment of the invention as described is merely illustrative and is not to be construed in a limiting sense, as various changes may be made without departing from the spirit of the invention or the scope of the appended claims.

We claim:

1. A blower wheel, comprising in combination, side rings, each of the said side rings having a plurality of lateral sockets on their inside surfaces, a plurality of blades between the rings, each of the blades having tabs engaging the

said sockets, a shaft, and a means for attaching the shaft to the said blades.

2. A blower wheel, comprising in combination, side rings having a plurality of annularly spaced longitudinally embossed flat sockets, a plurality of blades having tabs fastened in the said sockets, and a shaft attached to the said blades.

3. A blower wheel, comprising in combination, parallel side rings having a plurality of inwardly embossed sockets thereon, a plurality of parallel blades having end tabs securely engaging the sockets, the said blades being annularly spaced between the side rings, a shaft projecting outwardly through the centers of the side rings and a means for attaching the shaft to the said blades.

4. In a blower, an impeller, comprising in combination, parallel side rings, the said side rings having a plurality of annularly spaced embossed sockets and a plurality of blades having end tabs engaging the sockets and securely fastened therein.

5. In a blower, an impeller, comprising in combination parallel side rings having a plurality of annularly spaced sockets thereon, the said sockets being lateral to and on the inside of the said rings, and a plurality of blades between the rings and having means for engaging the said sockets.

6. In a blower, an impeller, comprising in combination, a plurality of longitudinally curved blades having arcuate end-stays and pointed tabs, and parallel side rings having means for securely engaging the said tabs.

7. In a blower wheel, an impeller, comprising in combination, parallel side rings having a plurality of annularly spaced longitudinally embossed flat sockets thereon, and a plurality of longitudinally curved blades, the said blades having arcuate end-stays and tabs fitting the said sockets and securely fastened therein.

8. In a blower, an impeller, comprising in combination, side rings having a plurality of inwardly disposed sockets, a plurality of blades, and means on the said blades for uniformly engaging the said sockets.

9. In a blower, an impeller blade, consisting of a strip of metal having curved ends, arcuate end-stays across the curved ends, and tabs projecting from the said end-stays.

10. In a blower, an impeller blade, consisting of a longitudinally curved strip, arcuate end-stays extending laterally across the ends of the strip, and tabs projecting diametrically from the said end-stays.

11. In a blower, an impeller ring, consisting of a flat hoop having a plurality of annularly and evenly spaced sockets on one side thereof, the said sockets each having a flat channel contiguous to the surface of the hoop and extending angularly to the circumference thereof.
